UNITED STATES PATENT OFFICE.

EUGENE O. BURNS, OF RENO, NEVADA.

TOY GUN.

Application filed February 3, 1925. Serial No. 6,614.

To all whom it may concern:

Be it known that I, EUGENE O. BURNS, a citizen of the United States, residing at Reno, in the county of Washoe and State 5 of Nevada, have invented certain new and useful Improvements in Toy Guns, of which the following is a specification, reference being had to the accompanying drawings.

This invention relates to toy guns, and 10 particularly to toy guns so constructed as to discharge an elastic band.

The general object of the invention is to provide a very simple toy gun of this character which may be in the shape of a gun 15 or pistol and which is so constructed that when an elastic band is placed in position around the muzzle of the gun and around the hammer and the trigger is pulled, the hammer will release the elastic band and the elasticity of the band will cause it to be discharged in a straight line toward the object aimed at.

A further object is to provide a device of this character which is very simple, which 25 cannot get out of order, and which is, relatively speaking, accurate.

A still further object is to provide a construction of this character which will permit the use of elastic bands formed of old 30 inner tire tubes.

My invention is illustrated in the accompanying drawing, wherein:

Figure 1 is a side elevation of a piston constructed in accordance with my invention;

Figure 2 is a top plan view thereof;

Figure 3 is an elevation with the cover plate 35 taken away and showing the latch cocked;

Figure 4 is a like view to Figure 3 but showing the action of the parts when the trigger is pressed.

Referring to this drawing, 10 designates the body of the gun, which is preferably 45 made of wood and formed to simulate a barrel 11, the bridge portion 12 of the gun, and the grip 13. The extremity of the barrel 11 is forked or notched, as at 14. The bridge portion of the gun is formed by recessing 50 the stock, as at 15. Disposed within this recess is a latch 16 pivoted at 17 and this latch at its upper end projects above the upper edge of the bridge or stock 12. The lower end of this latch is cut away to form a tooth 18, and coacting with this tooth is an angular detent 19 pivoted at 20 and formed on

its horizontal arm with an upwardly extending tooth 21 normally engaging the tooth 18.

Pivoted at the forward end of the recess 15 is a trigger 22 which is pivoted at 23 intermediate its length. The upper end of this trigger is connected by means of a link 24 with the lower corner of the angular detent 19. Thus it will be seen that when this trigger is pulled, the detent 19 will be retracted and will oscillate upon its pivot 20. The trigger is notched at 25 and a notch 26 is formed in the lever 16. Disposed with its ends in these notches is a bowed leaf 70 spring 27 which is held in place by means of a U-shaped keeper 28. Preferably a metallic stop 29 is disposed forward of the upper end of the trigger 22 so as to limit the forward movement of the trigger. The 75 rear end of the recess 15 is bounded by a stop 30 of rubber held in place by a metallic plate 31, in turn attached to the wall of the recess by means of a screw 32 or other like means. A guard 33 is attached to the 80 under side of the stop and to the grip 13.

In using the toy, a rubber band of suitable strength and approximately three inches in diameter is placed with one end in the notch 14 and the band is stretched 85 rearward and looped over the lever 16. When this band is over the lever 16, it pulls on the upper end of the lever and pulls the lower end of the lever against the tooth 21. If now the trigger be pulled, the tension of 90 the rubber band A will pull the upper end of the lever 16 forward because the lower end is released by the latch 19 and, of course, the band will be projected by reason of its own resilience to a considerable distance. 95 So long, however, as the trigger is unpulled the band will simply exert strain upon the upper end of the lever 16 and the lower end will be held against the tooth 21. As soon as the band has been projected and the trigger is released, the lever will have returned to its initial position by reason of the spring 27 acting upon the trigger and upon the lever 16. Of course, a cover plate 35 is used over the face of the recess 15, this cover plate being fastened to the walls of the recess by screws.

Obviously, I do not wish to limit myself to any particular variety of rubber band for use with this spring or toy gun, but I 110 have found in practice that rubber bands cut from the old inner tubes of Ford cars

are particularly good for the purpose. Any rubber band, however, may be used for this purpose.

It will be seen that a toy gun constructed 5 in accordance with this invention is not dangerous and even if the elastic band should strike the eye it will not hurt. Many changes may be, of course, made in the details of the device without departing from 10 the spirit of the invention.

I claim:—

1. A toy gun of the character described including a body having a handle and a barrel, a latch pivoted upon the body and having 15 its upper end extending above the upper edge of the body whereby an elastic band may be engaged with the forward end of the barrel and over said lever, a detent pivoted upon the body and adapted to engage 20 the lower end of the latch, a trigger, a spring urging the lower end of the trigger forward and the upper end of the latch rearward, and an operative connection between the

trigger and the detent to cause the latter to be retracted from its engagement with the latch when the trigger is retracted. 25

2. A toy gun of the character described comprising a body having a barrel and a grip, a latch pivoted upon the body and having its upper end projecting above the upper edge of the body, the lower end of the latch being provided with a tooth, an angular detent pivoted at one end upon the body, the other end of the detent being provided with a tooth adapted to engage with the tooth 30 on the latch, a trigger pivoted upon the body, a link connecting the upper end of the trigger with the lower end of the detent, a spring urging the lower end of the trigger forward and the upper end of the latch 35 rearward, whereby the detent may be withdrawn from its engagement with the latch when the trigger is retracted. 40

In testimony whereof I hereunto affix my signature.

EUGENE O. BURNS.
